CLAIM

The ornamental design for a hair styler, as shown and described.

DESCRIPTION

FIG. 1 is a front, right and top perspective view of a hair styler, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of portion "9" shown in FIG. 1. The evenly-spaced broken lines illustrate portions of the article and form no part of the claimed design.

The dot-dash broken lines in FIGS. 1 and 9 illustrate enlarged view indicators and form no part of the claimed design.

1 Claim, 9 Drawing Sheets(56)
